UNITED STATES PATENT OFFICE.

ALFRED G. HOLCOMBE, OF NEW YORK, N. Y., ASSIGNOR TO THE EQUITABLE ELECTRIC COMPANY, OF SAME PLACE.

ELECTRICAL CALL OR SIGNALING APPARATUS.

SPECIFICATION forming part of Letters Patent No. 336,643, dated February 23, 1886.

Application filed November 21, 1885. Serial No. 183,470. (No model.)

To all whom it may concern:

Be it known that I, ALFRED G. HOLCOMBE, a citizen of the United States, residing at New York, county and State of New York, 5 have invented certain new and useful Improvements in Electrical Call or Signaling Apparatus, of which the following is a specification.

This invention relates to that class of electrical apparatus designed to automatically transmit a call or one of a set of signals from a sub-station to a central station; and it consists of a call or signaling instrument embracing a signaling-disk actuated by a spring or other motor, provided with notches on its periphery arranged to indicate the calls or messages, and having a pointer or index secured to its shaft adapted to be set opposite the calls or signals marked on the case of the instrument, a spring pawl or dog carried by a pivoted arm arranged to catch into the teeth of and hold the signaling-disk when its attached pointer is set opposite any of the call-messages, a make-and-break contact-point carried by the pivoted arm, a lever arranged to lock the pivoted arm, a push-button for actuating the lever to release the pivoted arm, and a stop-pin projecting from the side of the signaling-disk, which, by coming in contact 30 with the locking-lever, causes it to lock the pivoted arm when the disk has been rotated by its actuating-spring and the pointer is at the zero-mark.

In the accompanying drawings, forming part of this specification, Figure 1 is a front elevation of my electrical call-box with the cover removed, showing the mechanism in its normal locked position. Fig. 2 is a vertical section cut on the line $x-x$, Fig. 1; and Fig. 3 is 40 a view similar to Fig. 1, showing the arrangement of the devices when the instrument is operating.

The working parts are so made as to occupy but little space, and are contained in the cylindrical case a , on the cover a' of which are marked the signals or call-messages, as ordinarily done with this class of electrical apparatus. In the center of the case is fitted to rotate the main shaft b , and to its end, projecting through the cover a' , is secured the pointer or index c , provided with a knob, c' , by which it may be set opposite any of the

call-messages marked on the cover. One end of the spring d is fastened to the shaft b and the other end to the case a , the energy of the spring causing the shaft to rotate in the direction indicated by the arrow. d' represents a train of gears and retarding-escapement of the ordinary construction. The signaling-disk e is also secured to the shaft b , and its periphery is serrated or provided with teeth arranged in any desired manner, and in juxtaposition to this disk e is located the pawl or dog f , on the end of the flat spring g , which is attached to the arm h , pivoted at h' to the case a . This pawl f is held against the periphery of the disk e by means of the spiral spring i , connected between the end h^2 of the pivoted arm h and a stud in the case a ; and when the pawl f is against the periphery of the disk e , or in one of the spaces between the teeth, the contact-spring j , carried by the arm h , touches the pin or stop k , fitted in the insulated block k' , attached to the case a , as shown at Fig. 1.

The lever l , pivoted at l' to the case a , is so arranged that its upper end falls into a notch, h^3 , in the end of the arm h , which is inclined, as shown, and locks the arm with the pawl f pressed against the disk e , and with the pin j 80 against the stop or pin k . The lower end of the lever l is bent so as to strike the shaft b when the upper end of the lever is clear of the notch h^3 of arm h , and limits the movement of the lever. This bent part l^2 of lever l also acts 85 as a stop to the shaft b by the pin m , which projects from the face of the disk e , coming in contact therewith, as shown in Fig. 1, in which position of parts the index c points to the zero-mark on the cover a' . Just before the pin m comes against the bent part l^2 it strikes the side l^3 of the lever l , pushes the lower end of the lever away from the shaft b , and causes its upper end to engage in the notch h^3 of the arm h . To release the arm h of the lever l , a rod, 90 n , projects through the case a . Its inner end butts against the lever l below its fulcrum, and its outer end is provided with a push-button, n' .

The instrument is designed for use in a 95 closed circuit, one end, o , of the line being connected to the stud which holds the spring i , or to any other part of the case, and the other end, o' , to the stop k .

In setting the pointer *c* opposite any one of the call-messages marked on the cover *a'*, the teeth *e'* of the disk which may indicate the number of the call-box first pass by the pawl *f*, and then the teeth *e'* pass by the pawl which rests behind the one corresponding to the message indicated. This action winds up the spring *d* and moves the pin *m* away from the lever *l*. The flat spring *g* is sufficiently stiff and rigid to oppose the spring *d* in its tendency to turn the disk *e* backward. Now, to send the call-message to the central station, the push-button *n'* is pressed in, which, by its rod *n*, moves the lower end of the lever *l* against the shaft *b* and the upper end away from the notch *h'* in the arm *h*. This allows the spring *d* to turn the disk *e* in the direction indicated by the arrow. The teeth of this disk *e*, acting on the pawl *f*, move the arm *h* against the action of its spring *i* and break the circuit at the spring *j* and stop *k*, as shown in Fig. 3, each time a tooth passes by the pawl *f*, which breaks are indicated at the central station by a suitable receiving-instrument. The number 25 of the teeth *e'* which pass by the pawl *f* indicate, by breaks in the circuit, the desired message at the central station, and the teeth *e'* break the circuit to indicate the number of the call-box from which the message is sent.

30 The pin *m* is during this time moving back toward the lever *l*, and as soon as the last one of the teeth *e'* has passed by the pawl *f* this pin, by striking the side *l'* of the lever *l*, moves it and forces the upper end into the notch *h'* 35 of the arm *h*, the pin *m* finally resting against the bent end of the lever *l*, as shown at Fig. 1.

Having now described my invention, what I claim, and desire to secure by Letters Patent, is—

40 1. In an electrical signaling apparatus, in combination, a serrated signaling-disk actuated by a motor, a spring-pawl engaging in the serrations of the disk, a pivoted arm to which the spring of the pawl is attached, a locking-lever for holding the arm stationary, and a handle or pointer connected to the shaft of the disk, substantially as and for the purpose set forth.

50 2. In an electrical call-box, the combination, with a serrated signaling-disk actuated by a motor, of a pivoted arm provided with a contact-spring, a contact-stop, a locking-lever for holding the arm stationary with its contact-spring against the contact-stop, a spring-pawl connected to the pivoted arm and bearing in a serration of the disk when the arm is locked, and a spring attached to the arm to cause the spring-pawl to bear on the serrated disk when the arm is released, substantially 55 as and for the purpose set forth.

60 3. In an electrical call-box, in combination, a signaling-disk, a spring-acting pivoted arm, a spring-pawl attached to the arm, a locking-lever for holding the arm stationary, having its lower end bent in toward the shaft of the disk, and a pin projecting from the face of the disk to act as a stop thereto by coming in con-

tact with the bent end of the locking-lever, and also as a means to cause the lever to engage with the pivoted arm by acting against its side just before coming in contact with its bent end, substantially as and for the purpose set forth.

4. In an electrical call-box, in combination, 75 a serrated signaling-disk carried by a motor-shaft, a pivoted arm, a spring-pawl attached to the pivoted arm and bearing against the serrations of the disk, a locking-lever for holding the arm stationary, having its lower end bent in toward the shaft of the disk, and a push-button for acting on the lever to cause it to release the pivoted arm, substantially as and for the purpose set forth.

5. In an electrical call-box, in combination, 85 a serrated signaling-disk, *e*, actuated by a motor, a spring-pawl, *f g*, engaging in the serrations of the disk, a pivoted arm, *h*, to which the spring of the pawl is attached, a locking-lever, *l*, for holding the arm stationary, and a handle or pointer connected to the 90 shaft of the disk *e*, substantially as and for the purpose set forth.

6. In an electrical call-box, in combination, 95 a serrated signaling-disk, *e*, actuated by a motor, a pivoted arm, *h*, provided with a contact-spring, *j*, a contact-stop, *k*, a locking-lever, *l*, for holding the arm *h* stationary with its spring *j* locked against the stop *k*, a spring-pawl, *f g*, connected to the arm *h* and bearing in a serration of the disk *e* when 100 the arm is locked, and a spring, *i*, attached to the arm to cause the spring-pawl to bear on the serrated disk when the arm is released, substantially as and for the purpose set forth.

7. In an electrical call-box, in combination, 105 a signaling-disk, *e*, a spring-acting pivoted arm, *h*, a spring-pawl, *f g*, attached to the arm, a locking-lever, *l*, for holding the arm stationary, having its lower end, *l'*, bent in toward the shaft of the disk *e*, and a pin, *m*, 110 projecting from the face of the disk *e*, to act as a stop thereto by coming in contact with the bent end *l'* of the locking-lever, and also as a means to cause this lever *l* to engage with the pivoted arm *h* by acting against its side *l'* 115 just before coming in contact with its bent end, substantially as and for the purpose set forth.

8. In an electrical call-box, in combination, 120 a serrated signaling-disk, *e*, carried by a motor shaft, *b*, a pivoted arm, *h*, a spring-pawl, *f g*, attached to the pivoted arm and bearing against the serrations of the disk, a locking-lever, *l*, for holding the arm stationary, having its lower end, *l'*, bent in toward the shaft *b*, and a push-button, *n n'*, for acting on the lever to cause it to release the pivoted arm, substantially 125 as and for the purpose set forth.

In testimony whereof I have hereunto set my hand at New York, county and State of New York, this 18th day of November, 1885. 130

ALFRED G. HOLCOMBE.
